(57) **CLAIM**

The ornamental design for a cover, as shown and described.

DESCRIPTION

FIG. 1 is an isometric view of a top, left, and front side of an ornamental design for a cover;

FIG. 2 is an isometric view of a bottom, right, and rear side of the cover of FIG. 1;

FIG. 3 is a front elevational view of the cover of FIG. 1;

FIG. 4 is a rear elevational view of the cover of FIG. 1;

FIG. 5 is a right side elevational view of the cover of FIG. 1;

FIG. 6 is a left side elevational view of the cover of FIG. 1;

FIG. 7 is a top plan view of the cover of FIG. 1; and,

FIG. 8 is a bottom plan view of the cover of FIG. 1.

The dash-dash-dash broken lines are included for the purpose of illustrating portions of the cover that form no part of the claimed design. The appendix depicts additional embodiments of the claimed ornamental design for a cover.

1 Claim, 8 Drawing Sheets
